US00D990428S

(12) **United States Design Patent** (10) Patent No.: **US D990,428 S**
(45) Date of Patent: ** Jun. 27, 2023

(54) **MEDICAL DEVICE CONNECTOR**

(71) Applicant: **Physio-Control, Inc.**, Redmond, WA (US)

(72) Inventors: **Christopher G. Alviar**, Seattle, WA (US); **Neal Stanley Clark**, Snohomish, WA (US); **Barry D. Curtin**, Seattle, WA (US); **Neil G. McIlvaine**, Seattle, WA (US); **Peter Nazaroff**, Redmond, WA (US); **Zack Pahlman**, Redmond, WA (US); **Jeremy Wong**, Redmond, WA (US); **Christian Schneider**, Redmond, WA (US)

(73) Assignee: **Physio-Control, Inc.**, Redmond, WA (US)

(**) Term: **15 Years**

(21) Appl. No.: **29/798,565**

(22) Filed: **Jul. 8, 2021**

Related U.S. Application Data

(63) Continuation of application No. 29/708,046, filed on Oct. 2, 2019, now Pat. No. Des. 940,659.

CLAIM

The ornamental design for a medical device connector, as shown and described.

DESCRIPTION

FIG. 1 is a front view of a medical device connector; FIG. 2 is an enlarged perspective view of a front view of the medical device connector shown in FIG. 1;

FIG. 3 is a top view thereof;

FIG. 4 is a front view thereof;

FIG. 5 is a back view thereof; and,

FIG. 6 is a side view thereof.

The dashed broken lines depict portions of the medical device connector that form no part of the claimed design. The dot-dashed broken lines represent boundaries of the claimed medical device connector and form no part of the claimed design.

1 Claim, 4 Drawing Sheets
